UNITED STATES PATENT OFFICE.

JOSEPH C. SPAETH AND BOHUMIR VINAR, OF DWYER, WYOMING.

SILO-MATERIAL-HANDLING MECHANISM.

1,168,123.

Specification of Letters Patent. Patented Jan. 11, 1916.

Application filed April 9, 1914. Serial No. 830,770.

To all whom it may concern:

Be it known that we, JOSEPH C. SPAETH and BOHUMIR VINAR, citizens of the United States, residing at Dwyer, in the county of 5 Platte and State of Wyoming, have invented certain new and useful Improvements in Silo - Material - Handling Mechanism, of which the following is a specification.

This invention comprehends certain new 10 and useful improvements in silos and has for its primary object to provide an underground silo of improved and simplified construction and which will be highly efficient in use.

Another object is to construct a sectional 15 silo which may be readily assembled or taken apart and which may be formed of such material that the parts will not be subject to the changes in the climate, thereby eliminating danger of the parts warping and admitting dampness and moisture to the contents of the silo.

Another object is to provide a device of 20 this character including a shaft offset from the main portion of the silo, whereby a bucket may be lowered and raised in the shaft by means of a cable extending downwardly in the main portion of the silo.

A still further object of the invention is 25 to generally improve and simplify the construction and operation of devices of this character and increase the efficiency thereof without materially increasing the cost of the same.

With these and other objects in view as 30 will become more apparent as the description proceeds, the invention consists in certain novel features of construction, combination and arrangement of parts as will 35 be hereinafter more fully described and claimed.

For a complete understanding of our invention, reference is to be had to the following description and accompanying drawings, in which—

Figure 1 is a longitudinal vertical section through the upper portion of a silo constructed in accordance with our invention, Fig. 2 is a top plan view of the 40 silo with the hood removed, Fig. 3 is an elevational view of a portion of the bucket and the suspending and operating means for the same, Fig. 4 is an enlarged detail view of the latch mechanism carried by the bucket, Fig. 5 is a fragmentary detail view, showing the lower portion

of the bracing frame and the manner in which the same is connected with the bucket handle, and Fig. 6 is a detail sectional view of the upper central portion of the hood with the ventilation pipe projecting there-through and having the funnel and vane mounted thereon. Fig. 7 is a cross section on the line 7—7 of Fig. 1.

Referring in detail to the drawings by numerals, I designates the sections of the main portion of the silo which are of substantially circular form and which have their upper and lower edges resting upon one another. The sections 1 are secured together by bolts 2 or other suitable means engaged through the inwardly directed angle irons 3, the opposite angles of which are secured to the sections 1, along the edges thereof. Any number of sections 1 may be employed, it being understood that the connecting sections are all beneath the ground and a ladder 4 is secured to the inwardly directed angles of the angle irons 3, preferably adjacent the opening 5 in the wall of 50 the main or body portion of the silo, said opening 5 being formed by cutting away a portion of each section 1.

It will be understood that the opening 5 extends longitudinally the full length of the 55 silo and a shaft is formed by substantially U-shaped members 6 having their edges resting upon one another and positioned outwardly of the opening 5, said substantially U-shaped member 6 being preferably formed 60 with the sections 1 of the main portion of the silo. It will be understood that the right angled members or angle irons 3 are extended along the opposite edges of the substantially U-shaped members 6 and the bolts 2 65 engaged through the inwardly directed angles of said angle irons 3, along the edges of the members 6 serve to securely fasten together said members 6 and prevent moisture from entering the shaft or silo body. 70

Within each end of the shaft and secured to the inner face thereof is a channel iron guide 7, which extends longitudinally of the shaft and projects for a slight distance above the same, the upper end of each channel iron 75 guide 7 being flared, as shown at 8, whereby the rollers 9 mounted upon the pinions 10 projecting from the portions of the handle 11 secured to the opposite sides of the bucket 12, may readily enter said channel iron guides 110 7 to guide the bucket 12 in its vertical movement in the shaft. The handle 11 is prefer-

ably of substantially U-shaped form, with its main portion extending transversely above the bucket 12, the lower extremities of said handle 11 being pivoted to the outer face of the sides of the bucket 12, adjacent the bottom thereof, as shown at 13.

Secured to the central or main portion of the handle 11 is the looped member 14, in the eye 15 of which is secured one end of a cable 16 connected with a suitable pulley 17, such as employed in the well known Weston tackle. The pulley 17 is mounted in a supporting bracket 18, which is carried by the hook 19 engaged in the depending eye 20 of the carriage 21. The upper portion of the carriage 21 is bifurcated and the apertured sides thereof extend upwardly upon the opposite sides of the inclined track 22 which is formed of an I-beam, said carriage 21 having a pair of wheels 23 engaged upon each lower flange of the track 22. When the carriage 21 is at the upper end of the inclined track 22, the bucket 12 is directly above the shaft and further movement in this direction of the carriage 21 upon said track 22 is prevented by the stop 24. Movement of the carriage in the opposite direction upon the track 22 is limited by the lower stop 25, a spaced distance from the lower end of the track 22. The track 22 is supported by the post 26, the lower end of said track 22 being mounted in the upper end of said post which latter is spaced a suitable distance from the silo.

By proper manipulation of the chain 27 connected with the pulley 17 and depending in the main or body portion of the silo, the operator may readily draw the carriage 21 to position at the upper end of the track 22 and above the shaft. By the proper operation of the cord 28, the operator may also withdraw the stop member 29 from the track 22, said stop 29 being carried by the carriage 21 and normally engaged through a suitable opening in the track 22 forwardly of one of the wheels 23 of the carriage 21, to prevent movement of the said carriage toward the lower end of said track 22. After the stop member 29 has been withdrawn from the track 22, the carriage 21 and bucket 12 will move by gravity toward the lower end of the track 22. Movement of the carriage 21 in this direction will be prevented, however, by the lower stop member 25, previously mentioned. About the same time that the carriage 21 engages the lower stop member 25, the bucket 12 will be opposite the latch engaging arm 30 which extends downwardly and toward the silo, from the track 22, the upper end of said arm 30 being secured to the track 22 at its under face and adjacent the lower end thereof. The latch engaging arm 30 is braced by means of the brace bar 31 connected therewith and with the track 22. The pivoted

triangular latch releasing member 32, mounted upon the handle 11 engages the free end of the latch arm 30, as the bucket 12 moves to position opposite said arm 30, thereby causing the pivoted latch releasing member 32 to swing upon its pivot 33 and draw the latch 34 from within the latch opening 35 in the upper edge of the bucket 12, to permit said bucket 12 to swing to inverted position and thereby release the contents of said bucket, it being understood that the latch 34 is connected with one free corner of the triangular pivoted latch releasing member 32, by means of the cord 36.

After the contents of the bucket 12 have been deposited upon the ground between the post 26 and the silo, the operator, while within the silo, may manipulate the chains 27 to return the carriage 21 and bucket 12 to position above the shaft with the wheels 23 of the carriage 21 at the upper end of the track 22. This return of the carriage 21 and bucket 12 to normal position above the shaft is preferably accomplished by pulling downwardly upon both chains 27 and after the stop member 29 has been allowed to enter the opening provided therefor in the track 22 to prevent downward movement of the carriage 21 upon the track 22, the operator may manipulate the chains 27 to allow the bucket 12 to descend in the channel guides 7 while the bucket is still in inverted position. After the bucket 12 has reached the desired point in the shaft and channel guides, the operator may readily return said bucket 12 to upright position by swinging the same upon the pivot members 13 upon which the lower ends of the handle 11 are mounted. When swinging the bucket 12 to upright position, the upper end thereof swings through the opening 5 and as soon as said bucket is in proper position, the latch member 34 will automatically engage in the latch opening 35 provided therefore in the upper edge of said bucket 12 and prevent said bucket 12 from swinging in the handle 11. It will be understood that the chains 27 and rope 28 pass over a roller 36 rotatably mounted upon the shaft 37 which has its opposite ends secured to the upper edge of the main or body portion of the silo in such manner that the main portion of said shaft is positioned over the upper end of the opening 5.

In order to prevent the handle 11 and bucket 12 from swinging independently of the carriage 21, we have provided a substantially U-shaped bracing frame 38 which has its main portion engaged through the carriage 21 by the legs of said substantially U-shaped bracing member 38 extending downwardly from opposite sides of the frame 21 and have their lower extremities bifurcated, as shown at 39, and engaged upon the op-

posite sides of the main portion of the handle 11. It will therefore be seen that as the carriage 21 moves toward the opposite ends of the track 22, the handle 11 and 5 bucket 12 will be rigidly held in proper position beneath the same and prevented from swinging to either side or back and forth. This will permit the operator to readily release the member 29 to readily release the 10 bucket 12 and permit the same to descend between the channel guides 7, as soon as the carriage 21 has been secured at the upper end of the track 22.

It will be understood that a hood 40 is 15 positioned upon the ground around the edge of the uppermost section and has a substantially conical top 41, through the apex 42 of which projects the upper end of the ventilation pipe 43 which extends downwardly against the inner face of the top 41 and then against one side of the main or body portion of the silo, said ventilation pipe 43 being preferably formed of removable sections which may be readily attached and connected by means of locking lugs 44 and bayonet slots 45 or any other suitable means, as the ensilage is removed from the silo. Rotatably mounted upon the upper extremity of the ventilation pipe 20 30 43 is an inlet elbow 46, the free end of which is flared, as shown at 47, whereby air may readily enter the ventilation pipe and be conducted to the interior of the silo. A ring 47 projects from the turned portion of the 35 elbow 46 and preferably extends in an opposite direction to that in which the free end of said elbow extends, whereby the elbow may be readily rotated by the air currents, as will be readily understood.

40 It will be seen that owing to the manner in which our silo is constructed, it may be readily operated by one man, instead of requiring the time and services of two or more men, as has heretofore been necessary 45 with other forms of silos, and as we have employed metal in constructing the silo, and place the same below the ground surface, the silo requires no painting and danger of the ensilage freezing is eliminated. Further, 50 deterioration of the ensilage is avoided, as it is impossible for air to reach the same by entering the silo between the parts thereof, as in the silos formed of wood and the like and located above the ground surface, and 55 it is further impossible for the silo to be affected or blown down by air currents, as frequently happens to the above ground

silos. It will also be noted that the bucket will be guided in the shaft should the chain supporting same break and as the operator 60 is invariably within the circular body portion of the silo when operating the bucket, danger of injury to the operator, should the chains break or any other accident occur to the bucket operating mechanism, will be 65 eliminated.

While we have shown and described the preferred embodiment of our invention, it will be understood that minor changes in construction, combination and arrangement 70 of parts may be made without departing from the spirit and scope of the invention as claimed.

What is claimed is:—

1. In a device of the class described, a 75 shaft, guide members extending longitudinally of said shaft and projecting from the upper end thereof, the upper extremities of said guide members being flared, a bucket adapted for vertical movement between said 80 guides, means carried by said bucket for engagement with said guides, a carriage, said bucket being suspended from said carriage, a guide roller carried by one wall of said shaft, a track for said carriage, means 85 for locking said carriage against movement upon said track, means engaged over said guide roller and connected with the locking means to release the same, and means engaged over said roller for controlling movement of said carriage between said guides. 90

2. In a device of the class described, a shaft, a track positioned upon an incline and having its upper end extended over the shaft, a carriage mounted for movement 95 upon said track, means for locking said carriage at the upper end of said track, means for releasing said locking means, a pulley suspended from said carriage, chains mounted upon said pulley, a bucket suspended by said chains, a handle carried by said bucket, a latch member carried by said handle and engaged with the bucket to prevent turning of the latter, and a latch engaging arm at the lower end of said track 100 105 for engagement with the latch member to disengage the latter from the bucket.

In testimony whereof we affix our signatures in presence of two witnesses.
